UNITED STATES PATENT OFFICE

ALBERT E. ROBINSON, OF CINCINNATI, OHIO, ASSIGNOR TO THE AMERICAN TOOL WORKS COMPANY, OF CINCINNATI, OHIO, A CORPORATION OF OHIO

LAPPING MACHINE

Application filed April 13, 1931. Serial No. 529,736.

My invention relates to lapping machines for lapping gears in mesh with each other.

It is the object of my invention to provide novel means whereby gears of different kinds may be lapped; further, to provide novel means for placing the arbors on which the gears being lapped are mounted in various relations to each other for interlapping bevel gears and similar kinds of gears and interlapping spur gears and similar kinds of gears; and, further, to provide novel means for applying resistance to the driven gear being lapped in order to supply lapping pressure between said gears.

15 The invention will be further readily understood from the following description and claims, and from the drawings, in which latter:

Fig. 1 is a front elevation of my improved device.

20 Fig. 2 is a plan view of the same, partly broken away, showing a spindle supporting a plurality of bushings and gears, and partly broken away.

25 Fig. 3 is a cross-section of the same, taken on the line 3-3 of Fig. 1, and partly broken away.

Fig. 4 is a vertical sectional detail view of the same, taken on the line 4-4 of Fig. 10, and partly broken away.

Fig. 5 is a vertical section of the same, taken on the line 5-5 of Fig. 10, and partly broken away.

Fig. 6 is a side view of my improved device, partly broken away.

Fig. 7 is a cross-sectional detail view, taken in the plane of the line 7-7 of Fig. 6, and partly broken away.

Fig. 8 is a vertical section of my improved device, taken on the line 8-8 of Fig. 10, partly broken away, and showing a number of spur gears.

45 Fig. 9 is a vertical section of my improved device, taken on the line 9-9 of Fig. 2, and partly broken away; and,

Fig. 10 is a plan view of my improved device arranged for lapping spur gears, and partly broken away.

The present invention is an elaboration of the invention shown, described and claimed in my copending application for patent on improvements in lapping machines, filed in the United States Patent Office April 13, 1931, as Serial No. 529,735.

A frame 11 has a motor 12 mounted therein. This motor is instances as a reversible electric motor for rotating its rotor shaft 13 in reverse directions. A housing 14 is mounted on a bracket 15 of the frame and has an arbor 16 rotatable therein.

This arbor comprises a sleeve 17 in which there is a bore 18 and a tapered socket 19 at one end of the bore. (Fig. 8.) A spindle 21 has a tapered inner end 22 received in said bore, and a shank 23 on which one or more of the gears to be lapped are arranged to be secured. A threaded rod 27 is in the bore. It has a threaded end 28 screwing into the tapered end of the spindle. The head 30 of the bolt bears upon the end of the sleeve. The parts are clamped together endwise for securing the spindle in the sleeve.

The arbor is rotatable in ball bearings 31, 32, in the housing. It forms the driving arbor of the device.

The driving arbor has a pulley 33 thereon. (Figs. 2, 6, 8 and 10.) A pulley 34 is on the rotor shaft. A belt 35 is received about the pulleys for driving the arbor 16 by means of the electric motor in one or the other direction for lapping the respective faces of the teeth of the gears being lapped.

The outer raceways of the ball bearings 31, 32, are located in rabbets 37, 38, of the housing. A cap 39, is fixed to the end of said housing as by bolts 41. (Fig. 8.) The inner raceways of said ball bearings are spaced apart by a collar 43, one of said inner raceways being positioned by a shoulder 44 on said sleeve.

The driven pulley 33 has a hub 45 received about the opposite end of the sleeve, a nut 46 being threaded over the threaded end of the sleeve for clamping the hub, the inner race-sleeve for clamping the hub, the inner race-
5 ways and the collar therebetween upon said shoulder. A lubricant shield 47 is received about the opposite end of the sleeve and suitably held in place.

The gear on the driving arbor is shown as a bevel gear 51 in Figs. 1, 2, 6 and 9, and as a spur-gear 52 in Figs. 8 and 10. A number of gears can be located side by side on any of the arbors, depending on the lengths of the gear receiving shanks of the spindles, and 15 gears having holes of various diameters may be centrally mounted on the arbors by providing bushing structures of various diameters or providing spindles having gear receiving shanks of various diameters.

20 Fig. 8 shows a plurality of such bushing structures and gears to be lapped secured to one of the arbors.

The spindle 21 is provided with a flange 55 forming a shoulder for a bushing 56 rotatably connected with the spindle by means of a key 57, the gear to be lapped being received about the bushing and being rotatively connected therewith by a key 58. (Figs. 8 and 9.) The bushing has a flange 59 serving as 30 an end stop for the gear. Spindles having shanks of different lengths may be employed. (Compare Figs. 8 and 9.)

A plurality of such bushing structures may be located end to end on the spindle, and 35 any excess in length of the gear shank of the spindle may be filled with filling collars 62.

A washer 63 is received about the reduced end 64 of the spindle, a nut 65 having threaded connection 66 with said reduced end for 40 clamping the parts together endwise. Means for mounting the gears having holes of different diameters herein shown and described are not herein claimed, the same having been 45 shown, described and claimed in my afore-said copending application.

The frame is provided with guides 71 on which a saddle 72 is adjustable toward and from the arbor 16 in a path parallel with said arbor. (Figs. 1, 2, 6, 7 and 10.) The 50 adjustment is accomplished by means of a threaded rod 73 having threaded connection with a nut 74 secured to the saddle by a bolt 75. The screw rod has a handle 76 thereon for rotating the same. This forms a micrometer adjustment for the saddle on the frame. The saddle may be clamped in adjusted positions by a shoe 77 coacting with the guide and arranged to be clamped and unclamped by a nut 78.

60 Slides 81, 82, are adjustable on the saddle toward and from each other and toward and from the vertical plane in which the arbor 16 is located. (Figs. 1, 2, 3, 6, 9 and 10.) The saddle is provided with guides 83, along 65 which the slides are adjustable. Screw rods

84, 85, are rotatable and held endwise in bearings 86, 87, at the respective ends of said saddle, handles 88, 89, being fixed to said screw rods for adjusting the same. The respective slides are provided with nuts 90, 70 91, fixed to said slides as by means of bolts 92, 93. The screw rods are threaded into said nuts for adjusting the slides. This forms a micrometer adjustment for each of the slides for delicacy and accuracy of ad- 75 justments of the slides.

A swivel 97 is rotatable on the slide 81. (Figs. 1, 9 and 10). It has a journal stub 98 rotatable in an annular bearing 99 on the slide 81. T-bolts 100 have heads received in an annular T-slot 101 in said slide, nuts 102 threaded on the T-bolts clamping the swivel in adjusted positions.

A locking pin 105 is endwise shiftable in a guide 106, (Fig. 4), on the swivel and has a tapered locating end 107 received in tapered sockets 108, 109, in the slide 81 for locating the arbor on the swivel with its axis of rotation perpendicular to the axis of rotation of the arbor 16, as when lapping bevel gears, as exemplified in Figs. 1, 2 and 6, or parallel with said axis as when lapping spur gears, as exemplified in Fig. 10.

The locating plunger is axially movable by being provided with a rack 111 with 25 which a pinion 112 meshes, the pinion being on a shaft 113 in a bearing 114 on the swivel and having a handle 115 for operating the same. A spring 116 between a shoulder 117 on said plunger and a plug 118 in the 100 guide 106 and surrounding the shank of said plunger normally urges the plunger into its locating sockets.

The swivel 97 has a housing 121 thereon in which an arbor 122 is journaled. This arbor comprises a sleeve 123 and a spindle 124, and is constructed and mounted similarly to the arbor 16. Similar parts other than the arbor, sleeve and spindle, are designated by similar but primed reference numerals. 110 (Fig. 9).

Bushings of different diameters and widths may be received over the end of the spindle for accommodating gears having hubs of different widths and holes of different diameters.

In the present exemplification the hub 45' may form the inner member of a brake 127. (Figs. 1, 3 and 9). Brake shoes 128 provided with brake linings 129 coact with the 123 brake flange 130 of the brake hub 45'. The brake shoes are provided with slots 131 in which locating pins 132 are received, these pins being fixed to the inner wall 133 of a shell 134, this inner wall also serving as part 121 of the cap covering the end of the housing.

The brake shoes are pivoted on said pins and have movements on said pins toward and from the brake shoe. The brake shoes 125

are provided with contact bosses 135 at the respective sides of their pivots. Plungers 136 have heads 137 which coact with said bosses for urging the brake shoes toward the brake hub, these plungers acting on the respective ends of the respective brake shoes at both sides of the brake hub for equalizing braking pressure and friction about the brake hub and forming an extremely delicate and resilient friction urging means for the arbor operable in either direction of rotation of the arbor which is quickly responsive to differences in contact between the teeth of the gears being lapped.

15 A hollow bolt 138 is adjustable in a threaded bearing 139 at the position of each of the plungers. The bolt has a socket 140 in which the head of the plunger has movement, the plunger having a stem axially movable in a hole in the end wall of the socket, a spring 141 being located in said socket and said end wall for urging the plunger toward the brake shoe. (Fig. 3.)

20 A set screw 142 threaded in the wall of the threaded hole clamps the hollow bolt in adjusted positions, adjustment of the hollow bolt adjusting the tension of the spring. The stem of the plunger is provided with a collar 143 pinned thereto, forming a stop for inward movement of the plunger. A closing plate 144 is bolted to the end of the shell and has a hole 145 for accommodating the outer end of the arbor.

25 The slide 82 has a housing 151 thereon similar to the housing 121. (Figs. 1, 2, 5 and 10.) An arbor 152 is journaled in this housing. It comprises a sleeve 153 and a spindle 154. This arbor and its mounting are in all respects similar to the arbor 16 and its mounting, the parts being designated by similar reference numerals raised to the series 200. Suitable gears of various sizes may be mounted on the arbor 152, having similar mounting and attaching means as those provided for the gears on the arbor 16. (Fig. 8.) A bevel gear is shown mounted on the arbor 152 in Figs. 1 and 2. This arbor is shown in Fig. 10 as having its spindle and clamping rod removed, as in this view the machine is shown lapping spur gears located on the arbors 16 and 122, the arbor 152 being shown idle.

30 Gears to be lapped usually have their teeth cut or formed thereon and are then hardened. The hardening of the gears causes change of form in the gears or of some or all of the teeth, and the object of the lapping is to reduce the teeth to their proper forms.

35 The lapping is performed by meshing the gears to be lapped together, and supplying a lapping compound, as a mixture of powdered carborundum or grease, either manually or automatically to the teeth, as by means of a brush or a pipe feeding the compound to the gears to be lapped.

40 Figs. 1, 2, 6 and 9 show the device ar-

ranged for lapping bevel gears, for instance three bevel gears of a set forming for instance the intermeshing bevel gears of the back gear or reversing mechanism for the drill spindle of a radial drill. Fig. 10 shows the machine 70 arranged for lapping meshing spur gears.

In the former, the arbor 122 is arranged parallel to and in line with the arbor 152 and at right angles to the arbor 16. In the latter, the arbor 122 is arranged parallel with and at 75 the side of the arbor 16, the arbor 152 being shown idle.

45 In operation, rotation in a given direction is imparted to the arbor by operation of the rotor of the motor in one direction. This 80 causes rotation of the arbors in given directions, depending on the meshing relations of the gears being lapped. The adjustments of the slides are such that such meshing relation between the gears being lapped is obtained as to cause contact between the high points or most misshapen portions of the teeth thereof. As these high points are worn away during operation, the adjustable slides are 85 adjusted toward the stationary arbor for causing approach between the gears being lapped. These adjustments are micrometer adjustments for accurate approach between the gears, and such approach is continued either uninterruptedly or step by step until 90 the teeth of the gears are in proper form and have proper meshing relation.

50 Rotation of the driving arbor in one direction causes lapping of one of the sides of the teeth of each of the gears being lapped. Rotation of the driving arbor in the opposite direction causes engagement and lapping of the opposite sides of the teeth of the respective gears. These changes of direction may take place in steps during the lapping, or the 100 lapping of one of the sides of the teeth may 105 be completed before the lapping of the other of the sides of said teeth is begun.

55 During such lapping resistance is imparted to the driven arbors, causing pressure between the faces of the teeth being lapped for expediting the lapping. This is effected by the braking means, and the frictional resistance of the braking means is adjustable for adjusting the lapping pressure between the 110 teeth. This frictional resistance is preferably imparted by pivotally mounted shoes at the respective sides of a brake hub, and adjusting means for each end of each of the shoes, so that delicate adjustment for each direction 115 of rotation of the gears may be had, for providing a constant amount of resistance to rotation of the gears being lapped, with consequent even lapping of the teeth.

60 My improved device presents compact 120 means for the lapping of meshing gears, and simple and effective means whereby the machine may be changed for lapping bevel gears and the like or spur gears and the like, presents delicate pressure between the sides of 125 130

the teeth of the gears, and is strong, durable and simple in construction.

Having thus fully described my invention, what I claim as new, and desire to secure by Letters Patent, is:

1. In a gear lapping machine, the combination of a frame, a housing thereon, a shaft journaled on said housing, a saddle, a pair of housings on said saddle at the respective sides of the axis extended of said shaft, means for adjusting the respective housings of said pair of housings toward and from said axis, means for adjusting said saddle toward and from said first-named housing for simultaneously adjusting said pair of housings toward and from said first-named housing, a shaft journaled on each of said pair of housings and having axes of rotation which are normally in line with each other and at right angles to said first-named axis, means on the proximate ends of said shafts for receiving meshing gears to be lapped, and means for rotating one of said shafts.
2. In a gear lapping machine, the combination of a frame, a housing thereon, a shaft journaled on said housing, a saddle, means for adjusting the distance between said housing and said saddle, a pair of housings on said saddle at the respective sides of the axis extended of said shaft, means for adjusting the distance between said housings, a shaft journaled on each of said pair of housings and having axes of rotation which are normally in line with each other and at right angles to said first-named axis, means for rotating one of said shafts, means on the proximate ends of said shafts for receiving meshing bevel gears to be lapped, mounting means for one of said housings, and positioning means for said one of said housings whereby to arrange the shaft thereon into parallelism and offset relation with another of said shafts for receiving meshing spur gears to be lapped.
3. In a gear lapping machine, the combination of a frame, a housing thereon, a shaft journaled on said housing, a saddle, means for adjusting the distance between said housing and said saddle, a pair of housings on said saddle at the respective sides of the axis extended of said shaft, means for adjusting the distance between said housings, a shaft journaled on each of said pair of housings and having axes of rotation which are normally in line with each other and at right angles to said first-named axis, means for rotating one of said shafts, means on the proximate ends of said shafts for receiving meshing bevel gears to be lapped, mounting means on one of said housings for swiveling said shafts and swiveling means for swiveling said mounting means whereby to arrange one of said shafts into parallelism and offset relation with one of the shafts normally at right angles thereto for receiving meshing spur gears to be lapped.
4. In a gear lapping machine, the combination of a frame, a housing thereon, a shaft journaled on said housing, a saddle, means for adjusting the distance between said housing and said saddle, a pair of housings on said saddle at the respective sides of the axis extended of said shaft, means for adjusting the distance between said housings, a shaft journaled on each of said pair of housings and having axes of rotation which are normally in line with each other and at right angles to said first-named axis, means for rotating one of said shafts, means on the proximate ends of said shafts for receiving meshing bevel gears to be lapped, mounting means on one of said housings, for one of said shafts, adjusting means for said mounting means whereby to arrange one of said shafts into parallelism and offset relation with another of said shafts for receiving meshing spur gears to be lapped, said shafts including driven shafts, and adjustable braking means for said driven shafts.
5. In a gear lapping machine, the combination of a frame, a housing thereon, a driving arbor on said housing, a saddle, means for adjusting said saddle on said frame toward and from said housing, a housing at each end of said saddle respectively located laterally in opposite directions with relation to said first-named housing, an arbor on each of said last-named housings, means for shiftingly and swivelingly adjusting one of said last-named housings with relation to the others of said housings, whereby to arrange said last-named arbors in alignment, and arranging said arbor on said swivelingly adjustable housing parallel with and offset from said driving arbor, whereby to arrange said arbors for lapping meshing bevel gears and lapping meshing spur gears and means at the proximate ends of said arbors for securing meshing gears to be lapped.
6. In a gear lapping machine, the combination of a frame, a housing thereon, a driving arbor on said housing arranged to be driven in reverse directions, guideways on said frame extending parallel with said arbor, a saddle on said guideways, micrometer means for adjusting said saddle toward and from said housing, a housing on said saddle at one side of said guideways, an arbor thereon perpendicular to said guideways, guideways on said saddle perpendicular to said first-named guideways and extending to the other side of said first-named guideways, a slide on said second-named guideways, micrometer means for adjusting said slide on said second-named guideways toward and from said second-named housing, a swivel on said slide, a third housing on said swivel, a third arbor thereon, means for adjusting said swivel on said slide for adjusting the arbor thereon into parallelism with said first-named arbor and said second-named arbor, and means at the inner

ends of said arbors for attaching meshing gears to be lapped.

7. In a gear lapping machine, the combination of a frame, a housing thereon, a driving arbor on said housing arranged to be driven in reverse directions, guideways on said frame extending parallel with said arbor, a saddle on said guideways, micrometer means for adjusting said saddle toward and from 10 said housing, a housing on said saddle at one side of said guideways, an arbor thereon perpendicular to said guideways, guideways on said saddle perpendicular to said first-named guideways and extending to the other side of 15 said first-named guideways, a slide on said second-named guideways, micrometer means for adjusting said slide on said second-named guideways toward and from said second-named housing, a swivel on said slide, a third 20 housing on said swivel, a third arbor thereon, means for adjusting said swivel on said slide for adjusting the arbor thereon into parallelism with said first-named arbor and said second-named arbor, means at the inner ends of 25 said arbors for attaching meshing gears to be lapped and adjustable braking means for said second-named arbor and said third-named arbor.

8. In a gear lapping machine, the combination of a housing, an arbor thereon, means for rotating said arbor in reverse directions, an additional housing, an arbor thereon, means on the proximate ends of said arbors for securing meshing gears to be lapped, a brake 30 hub on said second-named arbor, brake shoes about said brake hub, a hood about said brake shoes, pivot connections between the middle portions of said brake shoes and said hood, spring pressed plungers on said hood acting 35 upon the respective ends of said shoes at the respective sides of said pivot connections, and means for adjusting the pressures of said spring pressed plungers, and arranged for causing lapping contacts of both sides of the 40 teeth of said meshing gears and for adjusting the pressures of said lapping contacts.

9. In a gear lapping machine, the combination of a housing, an arbor thereon, means for rotating said arbor in reverse directions, a slide, means for adjusting said slide toward and from said arbor, a swivel on said slide, a housing thereon, an arbor on said housing, means for adjusting said swivel on said slide 50 for adjusting the angle of said second-named arbor with relation to said first-named arbor, means on the proximate ends of said arbors for securing meshing gears to be lapped to said respective ends, a brake hub on said second-named arbor, said second-named 55 housing having an enlargement about said brake-hub, brake shoes in said enlargement, pivot connections between the middle portions of said brake shoes and said second-named housing, spring pressed plungers for 60 the respective ends of said brake shoes at the

respective sides of said pivot connections, and adjusting means for adjusting the pressures of said spring pressed plungers for adjusting the resistance to rotation in both directions of said second-named arbor for adjusting the pressure of the lapping contacts upon both sides of the teeth of said meshing 70 gears.

In testimony whereof, I have hereunto signed my name.

ALBERT E. ROBINSON.
